I. W. FISHER

CASEMENT WINDOW WEATHER STRIP

Filed Dec. 31, 1924

Inventor
I.W. Fisher

Attorney
Franklin J. D.

UNITED STATES PATENT OFFICE.

ISAAC W. FISHER, OF LAGUNA BEACH, CALIFORNIA.

CASEMENT-WINDOW WEATHER STRIP.

Application filed December 31, 1924. Serial No. 759,118.

The primary object of this invention is the securance of a close joint between the sash and frame of a casement window so as to exclude air, dust, and moisture.

5 Other objects and advantages will be apparent and suggest themselves as the nature of the invention is understood.

While the drawings illustrate an embodiment of the invention it is to be understood that in adapting the same to meet different conditions and requirements, various changes in the form, proportion and minor details of construction may be resorted to without departing from the nature of the 15 invention.

Referring to the accompanying drawings forming a part of the specification,

Figure 1 is a front view of a casement window provided with a weather strip embodying the invention,

Figure 2 is a sectional view on the line 2—2 of Figure 1,

Figure 3 is a detail view showing the sash swung into open position,

25 Figures 4 and 5 are detail views showing the mountings at opposite sides of the sash in which the weather strip is journaled, and

Figure 6 is a detail view of a portion of the sash as seen from the lower edge.

30 Corresponding and like parts are referred to in the following description and designated in the several views of the drawings by like reference characters.

The numeral 1 designates the frame, and 35 2 the sash of a casement window, the frame being provided with a sill or ledge 3 upon which the sash 2 closes. In accordance with the invention, the lower portion of the sash 2 is rabbeted upon the outer side as indicated at 4, said rabbet extending the full 40 width of the sash. Plates 5 and 6 are attached to opposite sides of the sash 2 and

close the ends of the rabbet 4, said plates being let into the sides of the sash so as to come flush therewith as indicated most clearly in Figure 3. A rod 7 is located within the rabbet 4 and is journaled in the plates 5 and 6 and one end is extended to provide an arm 8, the outer end of which is bent laterally into a grip at 9 to extend across a projecting portion 10 of the plate 5 to coact therewith to hold the rod in the required adjusted position when the weather strip is closed. A strip 11 is attached at one edge to the rod 7 and is transversely curved and when closed engages over the outer edge of the sill or ledge 3 as indicated most clearly in Figure 2.

When it is desired to open the sash 2, 60 the arm 8 is operated to swing the strip 11 into open position as indicated by the dotted lines in Figure 2 so as to clear the sill or ledge 3 and when the sash 2 is closed the grip 9 is operated to move the strip 11 so as to engage over the outer edge of the sill or 65 ledge 3 thereby forming a close joint to exclude air, dust and moisture.

What is claimed is:—

In a casement window, a sash having a rabbet at the lower portion of its outer face, 70 plates at opposite sides of the sash closing the ends of said rabbet, a rod journaled in said plates, a weather strip on the rod to extend below the sash and engage over the outer edge of the sill of the window, an arm 75 integral with one end of the rod having a grip parallel to the major portion of said rod and also integral with the rod, said grip being disposed in the rear of the sash, and one of the plates having a portion extending 80 to the rear of the sash to coact with said grip.

In testimony whereof I affix my signature.

ISAAC W. FISHER.
